[57] **CLAIM**

The ornamental design for a communication equipment and wire management rack, as shown and described.

DESCRIPTION

FIG. 1 is a front perspective view of a communication equipment and wire management rack, showing my new design;

FIG. 2 is a top plan view;

FIG. 3 is a rear perspective view;

FIG. 4 is a side elevational view;

FIG. 5 is a front elevational view;

FIG. 6 is a rear elevational view; and,

FIG. 7 is a front perspective view, similar to FIG. 1, but illustrating one arrangement of equipment and wires. The broken line showing in FIG. 7 is included for the purpose of illustrating environmental structure only and forms no part of the claimed design.

FIG. 1

FIG. 2

FIG. 5

FIG. 6

FIG. 7
